UNITED STATES PATENT OFFICE.

WILLIAM H. PERRY, OF CONCORD, NEW HAMPSHIRE.

DESIGN FOR A MONUMENT.

SPECIFICATION forming part of Design No. 23,959, dated January 22, 1895.

Application filed December 20, 1894. Serial No. 532,500. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for a Monument, of which the following is a specification, reference being had to the accompanying drawing.

This design consists in the peculiar configuration of the shaft and that of its several ornamental tablets, its cap, and in the different styles of finish, all of which will be fully set forth in the following specification and claim, and clearly illustrated in the accompanying drawing forming a part of same, on which both figures and letters will be used as reference.

The base 1, has four vertical sides which terminate at their top in an obtuse frustum 20 of a pyramid 2, upon which rests the pedestal which has four vertical sides 3, terminating at their top in an acute frustum of a pyramid 4, which is ornamented on one or more of its sides with a raised tablet 5. The lower 25 portion of the shaft has four tapering sides 6, and these are each ornamented with the polished tablets 7 7^a , of the configuration shown by the heavy border lines 8, and with the

raised tablets 9, their lower edge being beveled as seen at 10, and their upper edge being cut in the form of battlements 11; each corner of said tablets 9, being ornamented with a turret 12, upon the top of which is cut battlements 13. The cap consists of a four-sided acute frustum of a pyramid 14, each of which sides are ornamented with a raised tablet having a vertical front 15, and gable top 16; said frustum 14, terminating in the four-sided obtuse pyramid 17, having the raised tablets 18, of the configuration shown. The shaft is also provided with a raised tablet 19, adjoining the frustum 4, on each of its sides, the upper edge of which is beveled as at 20.

The several styles of finish are designated by letters,—A, representing rockwork; B, hammered-work, and C, polished-work.

What I claim is—

The design for a monument substantially as herein shown and described.

In testimony whereof I affix my signature in presence of two witnesses.

WILLIAM H. PERRY.
